UNITED STATES PATENT OFFICE.

FRANK B. KENNEY AND JOHN W. SIDEBOTTOM, OF LOWELL, MASSACHUSETTS, AS
SIGNORS TO T. C. ENTWISTLE COMPANY, OF LOWELL, MASSACHUSETTS, A COR-
PORATION OF MASSACHUSETTS.

PNEUMATIC LINT CLEARER FOR WARPING MACHINES AND THE LIKE.

Application filed March 10, 1923. Serial No. 624,107.

To all whom it may concern:

Be it known that we, FRANK B. KENNEY and JOHN W. SIDEBOTTOM, citizens of the United States, residing at Lowell, in the county of Middlesex, State of Massachusetts, have invented a certain new and useful Improvement in Pneumatic Lint Clearers for Warping Machines and the like, of which the following is a specification; reference 10 being had therein to the accompanying drawings.

The invention is an improvement in pneumatic lint-clearing or removing devices of the class of that described and claimed in 15 United States Letters Patent No. 1,339,182, granted May 4, 1920, upon application of James E. Farrell.

Like the device of the Letters Patent just mentioned, a device embodying the features 20 of the present invention is applicable to warping machines, looms, and other machines in which a series of yarns or threads travel onward side by side, and is adapted to serve the same general purposes as such 25 former device, namely those of clearing lint from the yarns or threads, combs, guides, drop wires, and the like, in the said machines; of preventing lint from becoming attached to the yarns or threads so as to 30 make "slugs" or bunches in the cloth into which the yarns or threads are woven; and of preventing the stop motion mechanisms 35 of the machines from being rendered inoperative through clogging by accumulated lint.

The invention provides a lint-clearer device of simpler and less expensive character and construction than the device of the said Letters Patent. The latter includes a 40 fan blower which is made to travel back and forth across the machine with which it is combined, by means of a rotating traverse screw having an endless or right and left screw thread, such travel being designed to cause the blast or current of air from the blower to act uniformly at all points in the width of the machine.

In the case of a pneumatic lint-clearer embodying the present invention the blower 45 that is employed occupies a definite location in the machine with which it is combined, and in order to secure the same result that in the case of the earlier device is secured

by traversing the blower bodily back and forth across the machine the blower of the present invention is mounted for swinging movement transversely of such machine, and through the agency of means actuated from the driving mechanism of the machine itself it is swung to cause the current of air therefrom to sweep back and forth transversely across the width of the machine.

An illustrative embodiment of the invention is shown in the accompanying drawings, in which latter,—

Fig. 1 is a front view of a portion of the width of a warping machine having the said embodiment applied thereto.

Fig. 2 is a side view of the warping machine and lint-clearer device of Fig. 1, certain parts having been removed on line 2, 2, of Fig. 1.

Fig. 3 is a view in vertical section in the plane of line 3, 3, of Fig. 1, showing a series of yarns or threads, the stop motion devices, etc.

Fig. 4 is a partly sectional view on a larger scale, showing the blower and a part of the means for oscillating the same.

Having reference to the drawings,—

The drawings represent a typical warping machine and the preferred arrangement, etc., of the lint-clearer device in connection therewith.

In Figs. 2 and 3, yarns or threads 1 are represented as extending through the back comb 2 as if coming from a warper-creel (not shown). The said yarns or threads pass from the back comb 2 over a measuring roll 3, under the movable falling-rod 4, Fig. 3, over the supporting roll 5, through the front comb 6, and over the front supporting roll 7, from which latter they pass down to the warper-beam 8, whereon they are wound by the action of the machine. Drop-wires 9, 9, 9, constituting the detectors of the stop motion mechanism are represented as hung in usual manner upon the yarns or threads at points between the rear supporting roll 5 and the front comb 6.

At 11 is a blower, applied at the top of the machine and arranged to produce a downwardly directed current of air to blow away lint from the yarns or threads during their passage from rear to front, and to keep the back and front combs, guides, drop

wires, parts adjacent the drop wires, in addition to the yarns or threads themselves, free and clear from lint.

In the case of this embodiment of the invention, the main support of the blower is a rod or shaft 10 which extends across the width of the machine, above the top of the latter, said rod or shaft being mounted in place by having its ends fixedly engaged with stands 111 rising from the tops of the side-frames of the machine. One of said stands is partly broken away in Fig. 2. In this instance, the blower is located at mid-width of the series of yarns or threads, which is an effective position for enabling it to keep the yarns or threads and the desired machine parts clear of lint. It is an electric fan, which is preferred, although the invention is not necessarily restricted in all instances to the employment of a fan blower.

To provide for swinging movements transversely of the machine, the fan is mounted between the depending arms of a bail or yoke 12 that hangs down from the supporting rod or shaft 10, the fan-casing being furnished with journals 13, 13, working in bearings in connection with the said arms. The bail or yoke occupies a vertical plane corresponding in general direction with the length of the yarns or threads, so that the fan swings in a vertical plane at, or substantially at right angles with said length.

To provide for the convenient connection of the yoke with the supporting rod or shaft 10, a collar 101 is placed upon said rod or shaft, said collar being furnished with a downwardly-extending stud or pin 102, and the bail or yoke is provided with a hub 121 which fits upon said stud or pin. A clamping screw 122 applied to the said hub serves to hold the bail or yoke in place upon the stud or pin, with capacity for adjustment up and down to vary the height of the fan above the yarns or threads, etc., and also with capacity for angular adjustment around the stud or pin in case it should be desired to vary the angle which the plane in which the fan swings makes relative to the length of the yarns or threads. The collar 101 is fixedly engaged with supporting rod or shaft 10 by means of a clamping screw 100, enabling the collar and fan to be adjusted upon said rod or shaft transversely of the machine, if desired.

According to the present invention, the means actuated from the driving mechanism of the machine by which the blower is swung to cause the current of air therefrom to sweep back and forth across the width of the machine, comprises in this embodiment a cam in connection with a gear-wheel 17 that is in mesh with a pinion 19 on shaft 20 of winding drum 26, and devices interme-

diate the said cam and the blower. The cam in question is constituted by a cam-groove 170 in the gear-wheel 17, and the main element of said devices is a rocker to which rocking movement is imparted from the cam. In this instance the rocker is a sleeve 14 that surrounds rod or shaft 10, it having fixed upon one end thereof by means of a clamping screw 160 an arm 16 which is connected by a link 32 with an arm 31 projecting from one of the journals 13 of the fan-casing, whereby when the sleeve 14 is rocked around rod or shaft 10 swinging movement is imparted to the fan-blower. Operative connection between the rocker and the cam is established by means of an arm 15 that is fixedly connected by a clamping screw 150 with the sleeve 14, a link 30 having its upper end engaged with the arm 15, and a lever 28 pivoted at 29 upon the machine-framing, provided with a cam-follower 27 working in cam-groove 170, and having the lower end of link 30 connected with it.

The fan 11 is shown provided with a guard 21 of usual character about its blades. In practice, suitable lead-wires *x*, *y*, Fig. 3, are connected with the fan. In Fig. 3 these lead-wires are merely indicated diagrammatically, to enable their general course to be traced. A suitable switch is provided for controlling the actuation of the fan. In this instance, such switch is indicated at 22, Fig. 3, located at the bottom of one end of the machine. The plunger 220 thereof is arranged to be depressed by a finger 23 upon the pedal-rockshaft 24, so as to close the switch and let the current flow only when the warping machine is running on high speed. With the switch arranged to be actuated from the pedal-rockshaft as just described, the blower is automatically set in action and commences to oscillate as soon as the warping machine is put on high speed. By reason of having the axis of oscillation disposed lengthwise of the machine, so that the plane of oscillation is transverse, i. e., widthwise of the machine, at right angles to the direction of the length of the yarns or threads, or substantially so, the blast of air is swept back and forth to clear the yarns, combs, drop-wires, etc., throughout the entire width of the machine. The effect of the blast or current as it acts upon the yarns, etc., is substantially uniform across the entire width of the machine.

In some instances, we contemplate substituting a nozzle for delivering air under moderate pressure in place of the electric fan which is illustrated in the drawings.

We claim as our invention:—

1. In a warping machine or the like, in combination, a supporting shaft, a blower mounted upon said shaft with capacity for swinging movement transversely of the ma-

chine, and means for swinging the blower to cause its blast to sweep across the width of the series of yarns or threads, comprising a sleeve upon the said shaft provided with arms, a cam, a cam-actuated member operatively connected with one of the sleeve-arms, and operative connections between a second sleeve-arm and the blower, to rock the latter when the sleeve is rocked.

2. In a warping machine or the like, a lint-clearer comprising a blower mounted for swinging movement transversely of the machine, an actuating cam, and a rocker actuated by said cam and connected with the blower for swinging the blower to cause its blast to sweep across the width of the series of yarns or threads.

3. In a warping machine or the like, a lint-clearer comprising a blower located at a fixed point in the width of the machine, and means actuated from the driving mechanism of the machine for swinging the blower to cause the current of air therefrom to sweep back and forth transversely across the width of the machine.

4. In a warping machine or the like, a lint-clearer comprising a blower, a yoke or supporting frame to which the blower is connected with capacity to rock or swing,

an overhead support for said yoke or supporting frame located at a fixed point in the width of the machine, and means for adjusting the yoke or supporting frame vertically upon the said overhead support.

5. In a warping machine or the like, a lint-clearer comprising a blower, a yoke or supporting frame to which the blower is connected with capacity to rock or swing, an overhead support for said yoke or supporting frame located at a fixed point in the width of the machine, and means for adjusting the yoke or supporting frame angularly in a horizontal plane upon the overhead support.

6. In a warping machine or the like, a lint-clearer comprising a blower, in combination with a yoke or supporting frame to which the blower is connected with capacity to rock or swing, and an overhead support for said yoke or supporting frame located at a fixed point in the width of the machine, one of the latter elements having a pin or projection and the other a sleeve adjustably fitting upon said pin or projection, and means for fastening said sleeve and said pin or projection together.

FRANK B. KENNEY.
JOHN W. SIDEBOTTOM.
